UNITED STATES PATENT OFFICE.

CARROLL POTTER, OF PHILADELPHIA, PENNSYLVANIA.

SECONDARY OR STORAGE BATTERY.

SPECIFICATION forming part of Letters Patent No. 769,403, dated September 6, 1904.

Application filed December 21, 1903. Serial No. 186,077. (No model.)

To all whom it may concern:

Be it known that I, CARROLL POTTER, a citizen of the United States, residing at the city of Philadelphia, in the county of Philadelphia 5 and State of Pennsylvania, have invented certain new and useful Improvements in Secondary or Storage Batteries, of which the following is a specification.

One object of the present invention is to provide for guarding against accidental detachment of plate-lugs from their connecting-strap.

Another object of the invention is to facilitate the operation of connecting the plate-lugs and their connecting-strap.

To these and other ends hereinafter set forth the invention, stated in general terms, comprises the combination, with the connected plate-lugs and connecting-strap, of bridge-pieces arranged between the lugs beneath the strap, whereby mechanical strength and stability are imparted to the structure; and it further comprises the combination, with a strap having beveled openings, of lugs adapted to penetrate said openings and respectively provided with lateral projections having beveled ends, said beveled portions facilitating burning and puddling; and the invention further comprises the improvements to be presently described and finally claimed.

The nature, characteristic features, and scope of my invention will be more fully understood from the following description, taken in connection with the accompanying drawings, forming part hereof; and in which—

Figure 1 is a side view, partly in section, of a strap embodying features of the invention. Fig. 2 is a side view of a lug embodying features of the invention. Fig. 3 is a side view 40 of a plate having a lug and strap connected in accordance with the invention, and Fig. 4 is an end view of a number of plates connected with a strap in accordance with the invention.

In the drawings, 1 is a connecting-strap, and 2 represents plate-lugs.

3 represents bridge-pieces which connect the lugs beneath the plate-strap. The bridge-pieces obviously impart mechanical strength 50 to the structure and prevent the lugs from working loose or becoming detached where

they are connected with the strap. The best means known to me at this time for making the described structure will now be explained.

The lugs 2 are provided with lateral projections 4, having beveled or chamfered ends. Two of these projections are placed in alignment and are burned together, thus making the bridge-piece 3. The fact that the ends are chamfered or beveled facilitates this burning and puddling. The strap is provided with beveled or chamfered openings 5, through which the lugs 2 are inserted and then burned and puddled, so as to connect them.

It will be obvious to those skilled in the art to which my invention appertains that modifications may be made in detail without departing from the spirit thereof. Hence I do not limit myself to the precise construction and arrangement of parts hereinabove set forth, and illustrated in the accompanying drawings; but,

Having thus described the nature and objects of my invention, what I claim as new, and desire to secure by Letters Patent, is—

1. The combination of a connecting-strap, plate-lugs joined thereto and depending therefrom, and bridge-pieces interposed between and attached to the lugs to relieve the strain at the joints of the lugs with the straps, substantially as described.

2. The combination with a connecting-strap of plate-lugs having integral lateral projections burned together to constitute bridge-pieces, substantially as described.

3. The combination of a connecting-strap, and plate-lugs burned thereto and provided with lateral projections burned together to constitute bridge-pieces, substantially as described.

4. The combination of a connecting-strap having chamfered openings, and plate-lugs adapted to said openings and provided with lateral projections having beveled ends, substantially as described.

In testimony whereof I have hereunto signed my name.

CARROLL POTTER.

In presence of—

W. J. JACKSON,
JAS. A. RICHMOND.
